UNITED STATES PATENT OFFICE.

MICHAEL HENRY McGUIRE, OF CLIFFORD, MICHIGAN, ASSIGNOR OF ONE-HALF TO
CLAYTON E. FREDERICKSON, OF ST. JOSEPH, MICHIGAN.

PORTABLE BATHTUB WITH HEATING APPLIANCE.

Application filed August 30, 1922. Serial No. 585,245.

To all whom it may concern:

Be it known that I, MICHAEL HENRY McGUIRE, a citizen of the United States, residing at Clifford, in the county of Lapeer and

5 State of Michigan, have invented a new and Improved Portable Bathtub with Heating Appliance, of which the following is a specification.

This invention has reference to improvements in that type of portable bath tubs that are equipped with attached appliances for heating the water and primarily my invention seeks to provide an improved portable bath tub of the character stated of a simple 10 and inexpensive construction that can be easily moved about and which effectively serves its intended purposes.

Another object of the invention is to provide a bath tub with oil burner attachments 20 therefor so arranged that the burner can be quickly and conveniently put into or out of action and in which the burner devices are so designed that they can readily be mounted on the tub supporting framing in such manner 25 that they are held out of view when assembled in connection with the tub, and which include a peculiarly constructed heating surface with which the water, that is placed within the tub, is kept in constant circulation.

In its more subordinate features, my invention embodies in a bath tub construction of the general type mentioned, the peculiar combination and novel arrangement of 35 parts, fully set forth in the following detailed description, specifically set out in the appended claims and illustrated in the accompanying drawings, in which:

Figure 1 is a perspective view of my improved portable bath tub,

Figure 2 is a longitudinal section thereof.

Figure 3 is a top plan view, parts being in horizontal section along the line 3—3 on Figure 2.

45 Figure 4 is a transverse section thereof taken through the burner on the line 4—4 on Figure 2.

Figure 5 is a detail perspective view of the hollow, water heating, casting and the combined circulating and drain pipe connected therewith.

In carrying out my invention I provide a bath tub of the conventional shape and finished in the usual way. In the present show-

ing the tub body proper is preferably formed 55 as a part of (or it may be attached to) a housing that surrounds the tub body, in the manner best shown in Figures 3 and 4.

The housing extends beyond the front and rear ends of the tub body to provide chambers, the forward one 2 of which is adapted 60 for receiving therein an oil reservoir 3, presently again referred to, and whose other chamber 4 constitutes a heating compartment, since it is within the said compartment 65 4 that the water heating means, presently fully explained, are located.

The bottom of the housing which surrounds the tub 1 is open and to facilitate the ready moving of the tub in place for use 70 or back out of the way, the said housing is mounted on casters 5—5, as shown.

At the rear end of the housing is a door 6 for affording ready access to the burner for lighting and turning off the same, when 75 necessary.

The water heating means, before generally referred to, comprises a flat hollow casting 7 having a solid and apertured front edge 70 which, when the parts are operatively 80 assembled, is set closely against the adjacent tub end with the apertures thereof in register with a pair of water passages 10—10 on the said rear end of the tub and to provide for making a tight joint of the hollow 85 casting 7 against the tub the said casting has vertical top and bottom flanges 71—72 for bolting the said casting 7 to the tub body.

At the rear or outer end, the hollow casting 7 has a pair of passages 73—73 to which 90 is coupled, in any well known way, the ends 80—80 of a combination water circulating and drain pipe 8.

The pipe 8, when the parts are assembled, passes under and in the direction of the 95 length of the tub and through a short lateral connection 81, it is joined with the drain 11 of the tub.

From the connection 81, the pipe 8 serves as a drain pipe since it extends forwardly 100 through the front end of the tub housing and has its projecting end fitted with a drain faucet 82, as shown.

The walls of the compartment, in which the heating devices are located, are lined 105 with asbestos, as at 14.

To keep the bather from the heated part of the tub, a false back 15 is located in the

rear end of the tub and to provide for the full benefit of the heated end of the tub the said false back 15 is apertured for the free circulation of the tub water therethrough.

5 17 designates any suitable type of cage or bracket and it is hung from the top of the front end chamber and is adapted for receiving the oil reservoir 3. A copper tube 19 connects with the said oil reservoir 3, 10 passes down and back under the tub and to the burner 20, which latter may be of any approved construction, and includes, as shown, a needle valve 21, the latter being positioned for being readily manipulated, 15 when the door 6 is opened.

From the foregoing description, taken in connection with the drawings, the complete construction, the manner of use and the advantages of my invention will be readily 20 apparent to those familiar with the handling and making of portable bath tubs.

It will be noticed that after the tub is filled to the desired level, by starting up the heating appliance, the water, as it becomes 25 heated, begins to circulate through the hollow casting or pipe 7 and continues to circulate under a uniform temperature, in the direction indicated by the arrows on the drawing so long as the heating devices are 30 in action.

Since the back wall of the tub is constantly kept hot by heat radiation from the burner, it follows that the said back wall materially assists in heating the water to 35 the desired temperature, it being understood that danger of burning the bather is practically eliminated by the false back 15. The open bottom housing provides for ample air circulation around the underside of the tub 40 and for feeding the burner.

What I claim is:

1. A portable bath tub comprising a tub body, an open bottom housing that surrounds the sides and ends of the said body, 45 the said housing having a compartment at one end with means for supporting an oil reservoir, a compartment at the other end, oil burner devices located in the said other end, a feed pipe connecting the said burner 50 devices and the oil reservoir, the burner devices including a control valve, the end of the housing adjacent the heater having an opening for providing access to the burner, a water heating receptacle cooperative with 55 the heater and a pipe connection that joins the said receptacle and the bottom of the tub, the said receptacle having an apertured end, and means for holding the said aper-

tured end in communication with the inside 60 of the rear end of the tub.

2. In a bath tub of the character described, an open bottom housing, a tub body disposed within the housing with its upper edge flush with the surrounding top edge of the housing at one end thereof, a fuel oil burner holding appliance located in the other end of the housing, a feed pipe that connects the oil holder and the heating appliance, the said heating appliance including a fuel feed 65 valve controlled burner, a water circulating means comprising a hollow casting in communication at one end with the interior of the back end of the tub body, a water circulating pipe connected with the other end of the hollow casting, the said pipe extending under the tub, a lateral connecting the pipe and the drain outlet of the tub, the hollow casting being located over the fuel oil burner, the outlet end of the water circulating 70 pipe extending through the wall of the housing and provided with a drain faucet.

3. As a new article, a portable bath tub with attached heating appliances, comprising an open bottom housing, a tub body having a drain outlet located within the said housing with its surrounding upper edge flush with the upper edge of the housing, the housing being extended at its opposite ends beyond the adjacent ends of the tub body 85 whereby to form front and rear end compartments, a fuel oil reservoir sustained in the front housing compartment, heating appliances located in the rear housing compartment, the said appliances including a fuel controlled oil burner, a feed pipe connecting the oil reservoir and the said burner, the housing having provisions for a free access to the burner devices, a hollow water holder located over the burner, said holder 90 having one edge open, means for holding the said open edge in tight communication through the back wall of the tub with the interior of the tub, a false back at the rear 95 end of the tub for preventing contact with the back wall of the tub when using the same, a circulating pipe which communicates with and passes down from the hollow water holder and extends lengthwise under the tub body and a lateral connecting the 100 said pipe with the drain outlet of the tub, said pipe having its end extended through the front end of the housing and provided with a drain faucet.

MICHAEL HENRY McGUIRE,
